(57) CLAIM

The ornamental design for a music player, as shown and described

DESCRIPTION

FIG. 1 is a front perspective view of a music player showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective reference view thereof with the symbols thereon; and,

FIG. 10 is a left side view of FIG. 9.

The broken lines immediately adjacent to the claimed areas in the views represent the boundaries of the design. The broken lines in the figures illustrate the portions of the design that form no part of the claim. None of the broken lines form any part of the claimed design.
